Inventor:

Laura M. Myers,

By Glenn S. Noble
Atty.

UNITED STATES PATENT OFFICE.

LAURA M. MYERS, OF CHICAGO, ILLINOIS.

SHINE OR GLOSS REMOVER AND NAP-PRODUCER.

1,401,719.

Specification of Letters Patent. Patented Dec. 27, 1921.

Application filed December 16, 1918. Serial No. 267,011.

To all whom it may concern:

Be it known that I, LAURA M. MYERS, a citizen of the United States, residing at Chicago, in the county of Cook and State of Illinois, have invented certain new and useful Improvements in Shine or Gloss Removers and Nap-Producers, of which the following is a specification.

When clothing becomes shiny or polished 10 on account of wear, the user frequently would desire to remove the shine or gloss so that the cloth will have its original appearance, but the ordinary brushes or cleaning devices very often accentuate or increase the 15 gloss instead of removing the same.

The objects of this invention are, to provide a device for removing the gloss or shine from clothing; to provide a device of this character which may be cheaply constructed 20 and will be conveniently used; to provide such a device in which the active elements may be readily renewed; and, in general, to provide such an improved device as will be described more fully hereinafter.

25 In the accompanying drawings illustrating this invention:

Figure 1 is a side view thereof; and

Fig. 2 is a cross sectional view.

I have discovered that garnet paper or 30 cloth, when properly applied, will serve to remove the gloss on clothing and will tend to produce or raise a nap thereon. This paper or cloth consists of a suitable fabric to which ground or pulverized garnet has been 35 applied in a manner similar to the way in which sandpaper is made.

In order to utilize such garnet paper in a 40 convenient manner, I provide a holder or support for the same, as shown in the drawings. This holder comprises a body portion 3, the upper part of which is rectangular in cross section, while the lower part is substantially circular. The garnet cloth 4 is applied to this body portion and secured 45 thereto in any convenient manner, being preferably wrapped around the same one or more times, as indicated in Fig. 2. This paper or fabric is held in position by the handle 5, which consists of an upper rounded portion 6 and a lower flat portion 7, which extends the full length of the body portion and is preferably slightly narrower than the body. This handle is secured in position by

means of screws or the like 8, which are conveniently located at either end thereof.

When the device is to be used, it is held by the handle portion, the flanges or flat portions 7 serving to protect the ends of the fingers from the goods to be acted upon. It will be noted that the semi-cylindrical lower portion of the device may be drawn sidewise across the goods and there will be a line contact which will be very effective in serving to raise the nap on the cloth, and thereby remove the gloss or shine.

By having the upper part of the body portion 3 made rectangular, flat surfaces such as are indicated at 9 are provided on either side of the device, and these surfaces may be used where larger areas are to be acted upon, or where better results may be obtained by such flat surface. The corners, such as indicated at 10, may be used along the seams or wherever it may be necessary to get into cracks or limited spaces.

By having several layers of the fabric around the body portion in the first instance, the user is enabled to utilize the device for a larger amount of work by cutting off the outer layer as it becomes worn and exposing the next inner layer. This may be conveniently done by running a knife along the edge, as indicated at 11.

While I prefer to use garnet cloth, it will be noted that other similar material with a sharp or crystalline surface may be utilized, for example, emery paper or the like.

Having thus described my invention, what I claim and desire to secure by Letters Patent is:

1. In a device for removing shine or gloss from clothes, the combination of a holder comprising a substantially rectangular body portion having a semi-cylindrical lower side, garnet paper wrapped one or more times around said body portion, a handle having a flat surface engaging with the paper on the flat side of the body portion, and means for fastening the handle to the body portion to secure the paper in position.

2. In a device of the character set forth comprising a new article of manufacture for removing shine from clothing, the combination of a body having flat sides and a rounded lower surface, a fabric provided with sharp crystalline grains applied to said

body, and a handle secured to the body and holding the fabric in position, the arrangement being such that the device will have two flat sides and a rounded bottom for engagement with the goods to be acted upon.

3. In a device of the character set forth for raising a nap on cloth, the combination of a wooden block, a fabric coated with

sharp crystalline grains applied to said block, and a handle secured thereto, said handle having flanges for engagement with the block, said flanges also serving to protect the fingers, the block being shaped so that flat or line surfaces may be employed when the device is applied to the goods.

LAURA M. MYERS.
